Atty.

UNITED STATES PATENT OFFICE.

ENOCH KAVANAGH, OF DES MOINES, IOWA, ASSIGNOR OF ONE-FOURTH TO H. P. CRAMBLETT AND ONE-FOURTH TO H. H. GERARD, BOTH OF DES MOINES, IOWA.

ADJUSTABLE PUNCH-HOLDER.

1,313,699.

Specification of Letters Patent. Patented Aug. 19, 1919.

Application filed March 6, 1917. Serial No. 152,485.

To all whom it may concern:

Be it known that I, ENOCH KAVANAGH, a subject of the King of Great Britain, and resident of Des Moines, Polk county, Iowa, have invented a new and useful Adjustable 5 Punch-Holder, of which the following is a specification.

The object of this invention is to provide an improved construction for a multiple 10 punch holder, with means for selectively placing individual punches into operative and inoperative positions.

A further object of this invention is to provide improved means for selectively 15 adapting any desired number of a series of punches into position for operation, or into inoperative position, to meet the requirements of a particular work in hand.

A further object of this invention is to 20 provide a simple and easily operated device for adjusting to operative or inoperative position any of a series of punches in a multiple punch holder.

My invention consists in the construction, 25 arrangement and combination of elements hereinafter set forth, pointed out in my claim and illustrated by the accompanying drawing, in which—

Figure 1 is an end elevation of a punch 30 holder constructed according to my invention. Fig. 2 is a side elevation of the same, partly in section. Fig. 3 is a plan of a gag plate used with the device.

Fig. 4 is a bottom plan of another punch 35 holder embodying my invention, illustrating the use of a plurality of rows of punches. Fig. 5 is a plan of one form of gag plate which may be used with the same.

In the construction of the device as shown 40 in Figs. 1, 2 and 3 the numeral 10 designates a head formed with an upwardly projecting shank 11 adapted to be secured in and to a punch press (not shown) in a common manner. A punch-holding plate 12 is removably 45 and replaceably mounted in a longitudinal groove in the bottom of the head 10, and is held by bolts 13. The plate or block 12 is formed with a plurality of longitudinally spaced vertical bores in which punches 50 14 are removably and replaceably mounted, and adapted for vertical sliding movement at times. The plate or block 12 also is formed with longitudinal slots 15 intersecting the bores for the punches 14, said slots 55 preferably being two in number and verti-

cally spaced, whereby a sufficient bearing is provided for the punches but the frictional engagement thereof with the bores is materially reduced, and freedom of movement is obtained when desired. The punches 14 60 preferably are formed with shanks of uniform diameter within the bores of the block 12, and with enlarged heads, the upper slot 15 of the block preferably opening to the top thereof and receiving said heads, which 65 limit downward movement of the punches in the bores; but said punches may be formed with variously sized punching tips at their lower ends, to suit the needs of the particular work desired to be done. 70

The head 10 is formed with a longitudinally extending, end-opening aperture, rectangular in cross-section, above and in alignment with the heads of the punches 14, and one or another of a plurality of gag plates 75 16, illustrated in Fig. 3 as an example of many forms which may be employed, is adapted to be slidingly mounted in said aperture. Each gag plate 16 is formed with one or more circular holes 17 longitudinally 80 spaced and of a diameter corresponding to or slightly larger than the diameter of the heads of the punches 14, and adapted to permit passage of said heads, and upward movement of the punches in their 85 bores, when said plate is positioned with said holes in vertical alignment with the said punch heads. When a hole 17 of the gag plate is in registry with the head of a particular punch, that punch is thereby rendered inoperative, it being permitted to pass 90 upwardly upon contact with the work when the head 10 descends in the operation of the machine. It is to be understood that the gag plate 16, to effect this result, must have a vertical dimension not less than the thickness of the piece to be punched; and I deem it preferable to employ a gag plate in any given machine of at least as great a 95 vertical dimension as the thickness of any material to be punched thereon. When no hole 17 of the gag plate 16 is in registry with the head of a particular punch 14, but an imperforate portion of said plate is in contact 100 with such head, that punch is thereby rendered operative and is in position to punch a hole whenever the head 10 descends in the operation of the machine. It is apparent that any combination of the punches of a 105 series may in this manner be employed at a 110

given time, depending upon the location and arrangement of the holes 17 of the gag plate employed, and upon the position of said plate in its seat.

5 To positively hold the plate 16 in adjusted position, I employ a spring 18 secured at one end as by a bar 19 and screw 20 to the top of one end of the head 10 and passing downwardly and crossing one margin 10 of the gag plate seat. Each gag plate 16 is formed with one or more marginal notches 21 adapted to be engaged by the spring 18 to hold the plate in whatever position it is placed, the location and spacing of said 15 notches depending upon the position and utility of the holes 17 relative to the positions of the punches 14.

It is apparent that several combinations of holes may be successively punched in a 20 given article, or in a large number of similar articles, without changing of punch holders or rehandling of the articles, by the use of this device. For example, assuming that the end punches 14 shown in Fig. 2 are 25 three-eighths inch in diameter, and the central punch one-quarter inch, and that the centers of said punches are uniformly spaced one inch apart. Then, if it is desired to punch an article, or a number of articles, 30 with three spaced holes in one location (corresponding to size and spacing of punches above described), and with two holes of three-eighths inch diameter and spaced two inches apart, in another location, and a 35 single hole of one-quarter inch diameter in still another location, it is necessary for the operator simply to first set his gag plate 16 (selected for such work) in such position that no hole 17 registers with any of the 40 heads of the punches 14 (or he may use an imperforate gag plate for such purpose); then by a sliding movement of the plate 16 he positions the plate so that one of the holes 17 registers with the head of the cen-

tral punch, in the meantime shifting the 45 article to the desired location; then, accompanied by another shift, he moves the gag plate to such position that holes 17 register with the heads of each of the larger end punches, and the central punch alone is 50 operative. This saves handling and rehandling of the articles to be punched, and changing of the punch holders, and results in the saving of a large amount of time and 55 labor.

In Fig. 4 I have shown an example of a holder in which the plate or block 12^a is of greater dimensions and equipped with a plurality of rows of bores for punches 14, and selection of which may be employed. A gag 60 plate such as 16^a is provided for each row or series of punches, and the operation is similar to that previously described, to effect the desired combinations.

I claim as my invention—

A punch holder formed with a plurality of bores and also formed with a groove intersecting said bores, punches removably and replaceably mounted in said bores, a plate slidably mounted in said groove and 70 adapted to extend across said bores, said plate being formed with a plurality of holes adapted to register selectively with said bores, whereby different combinations of said punches may be placed in inoperative 75 position and the remaining punch or punches be placed in operative position, said plate being formed with a plurality of notches, and a spring normally bearing upon said plate, carried by said punch holder and 80 adapted to be engaged selectively in one or another of said notches, whereby sliding movement of the plate positively is prevented.

Signed by me at Des Moines, Iowa, this 85 second day of December, 1916.

ENOCH KAVANAGH.
